UNITED STATES PATENT OFFICE

NATHANIEL E. LOOMIS, OF WESTFIELD, AND ALBERT H. TOMLINSON, OF ELIZABETH, NEW JERSEY, ASSIGNORS TO STANDARD OIL DEVELOPMENT COMPANY, A CORPORATION OF DELAWARE

PROCESS AND APPARATUS FOR CRACKING OIL

Application filed October 1, 1926. Serial No. 138,840.

This invention relates to improvements in processes and apparatus for cracking hydro-carbon oils having a relatively low boiling point, particularly light gas oil. However, 5 the improvements described are applicable in general to the treatment of oils which are largely in vapor phase at the cracking temperature and pressure.

The invention will be fully understood 10 from the following description, taken in connection with the accompanying drawing, in which the figure is a diagrammatic side elevation, partly in section, of a preferred form of apparatus.

15 In the drawing, reference numeral 1 denotes a pipe through which oil is supplied to a cracking coil 2, arranged in a furnace setting 3. The coil discharges through a pipe 4 into a header or distributing box 5 mounted about midway in an elongated vertical soaking drum or digesting chamber or zone 6. The drum is insulated by lagging 7 or in any other suitable way.

20 Branch pipes 8 and 9 extend respectively up and down in the drum 6 from the header 5. The stream of oil vapor divides in the header, part emerging from the upflow pipe 8 and part from the downflow pipe 9. The stream may contain some liquid oil, but will 25 be mostly oil vapor. The cross sectional area of each of pipes 8 and 9 is preferably about half that of pipe 4, so that a fairly even distribution of the stream between the top and bottom of the drum is effected.

30 A plurality of drawoff connections 10, in each of which a valve 11 is installed, serve for the withdrawal of the contents of the drum at various heights. The connections 10 discharge into header 12, which connects 35 with a pipe 13 fitted with a pressure control valve 14. A bubble tower 15, or other vapor separating means, receives the product from pipe 13. The bubble tower has a cooling coil 16 in its top, and in the installation shown 40 the oil to be cracked is used as the cooling material, entering the coil 16 through pipe 17 and emerging into pipe 1 leading to the cracking coil 2. The tower 15 is provided 45 with bell-cap plates 18 or equivalent means. 50 Condensate is withdrawn from a pan 19 in

the tower through pipe 20 to the cooler 21 and receiver 22. Oil may be supplied for recycling from receiver 22 through valved pipe 23 to the main oil line 1, (through a collecting tank and pump, not shown), or may 55 be otherwise disposed of. Vapors are taken off from the tower through a pipe 24 to a cooler 25, the condensate from this cooler is received in a tank 26, and the residual gas and vapor are vented through pipe 27. A 60 valved pipe 28 opens into the lower portion of drum 6, for supplying a temperature-controlling fluid thereto, which may be oil from line 1.

In a typical operation according to the 65 present invention, a continuously flowing stream of light gas oil is highly heated under pressure in the coil 1, so that it emerges therefrom at a vaporizing and cracking temperature, which may be about 890° F. under a 70 pressure of 600 lbs. sq. in. The stream of heated oil is discharged into the header 5 and divides as above described. The liquid level in the drum is maintained at a low point by opening the valve 11 in the lowest connection 75 10, the other valves 11 being closed.

We have found that in the predominantly 80 vapor phase cracking of light gas oil there are usually heavy liquid components of the oil which are converted into coke if allowed to accumulate in the drum. It is therefore desirable, in operations of the type described, to draw off liquid oil in a manner to prevent the accumulation of a large body of liquid, 85 and the resulting formation of extensive coke deposits in the drum.

The temperature in the drum may be controlled as desired, but should usually be not much lower than that at the outlet of coil 2, for example about 820° F. The contained 90 heat of the oil causes cracking to take place in the drum. The temperature therein may be controlled if necessary by introduction of oil through pipe 28, or in other suitable ways. The pressure in the drum may be about 375 95 lbs. sq. inch, the valve 14 being set to open at the desired pressure. Vapors and liquid from the drum pass together through pipe 13 to the vapor separating and condensing system. 100

Injection of the stream from the coil into the drum at points adjacent its top and bottom promotes circulation throughout. The formation of a body of inert gas at the top of the drum, and of stagnant liquid at its bottom, are avoided. By maintaining circulation and withdrawing liquid from the drum as described, we are able to secure efficient conversion without objectionable coke formation. The level at which the liquid is permitted to stand in the drum may be higher when stocks of low coke-forming characteristics are being cracked. In such cases withdrawal from an intermediate level is preferred. The upper connection 10 may be used if cracking substantially in liquid phase is desired. In general, the relation between the liquid and vapor spaces in the drum is regulated in such manner as to secure efficient cracking without objectionable formation of coke. Liquid and vapor are taken off together from that connection 10 which is selected for withdrawal.

Various changes and alternative procedures may be made within the scope of the appended claims, in which it is our intention to claim all novelty inherent in the invention as broadly as the prior art permits.

We claim:

30 1. Process of cracking hydrocarbon oil in an elongated vertical soaking drum insulated against loss of heat, comprising heating a stream of oil to a vaporizing and cracking temperature, dividing the resulting stream of hot oil vapor, passing a portion of the stream into an upper part of the drum, passing another portion of the stream into a lower part of the drum, and withdrawing all vaporous and liquid products of conversion together from an intermediate point in the drum.

45 2. In the process of cracking hydrocarbon oil that includes heating the oil to a vaporizing temperature under pressure in a coil and passing the hot oil into an elongated vertical soaking drum under conditions to permit cracking therein substantially in sole consequence of the contained heat of the oil, the improvement that comprises discharging oil vapor from the coil into the drum in longitudinally directed streams at widely spaced points therein, whereby circulation of the charge in the drum is obtained, and withdrawing vaporous and liquid products together from a low point in the drum.

60 3. Apparatus for use in cracking hydrocarbon oil, comprising an elongated vertical soaking drum, a conduit for delivering a stream of hot oil vapor into the drum, a branched discharge pipe within the drum communicating with the conduit and adapted to discharge the oil in oppositely directed streams longitudinally of the drum at widely spaced opposite points in the drum, a plurality of valved outlet pipes arranged in

spaced relation longitudinally of the drum, a header communicating with said outlets and a pipe communicating with said header and affording the sole outlet for both vapor and liquid products from said drum.

4. The process of cracking hydrocarbon oil which comprises heating the oil to a vaporizing and cracking temperature, dividing the hot oil vapor into streams, passing one stream of the vapors into the vapor space of a digestion zone, withdrawing all vaporous and liquid products together from the lower part of the zone in sufficient volume to maintain a body of liquid hydrocarbons in the lower portion only of the zone, and passing another stream of the vapors into the lower portion of the zone below the level of the liquid.

5. In the process of cracking hydrocarbon oil that includes heating the oil to a vaporizing temperature under pressure in a coil and passing the hot oil into an elongated vertical soaking drum under conditions to permit cracking therein substantially in sole consequence of the contained heat of the oil, the improvement that comprises discharging oil vapor from the coil into the drum in longitudinally directed streams at widely spaced points therein, whereby circulation of the charge in the drum is obtained, and withdrawing vaporous and liquid products together from one point in the drum.

6. The process according to claim 5 in which the temperature of the oil in the drum is controlled by the introduction of controlled amounts of fresh feed stock directly into the drum.
